ARTICLE CARRIER

Homer W. Forrer, East Point, Ga., assignor to The Mead Corporation, a corporation of Ohio
Filed July 17, 1961, Ser. No. 124,405
1 Claim. (Cl. 220—113)

This invention relates to article carriers and more particularly to an article carrier having integral shallow, medial and transverse partitioning elements and separate cushioning partition elements for substantially increasing the depth of either or both the integral medial and transverse partitioning elements thereby to provide additional protection between adjacent articles packaged in the carrier.

In my Patent 2,537,452, issued January 9, 1951, and owned by assignee of this invention, a sturdy and reliable carrier is disclosed which is constructed of a single paperboard blank and which is specially adapted to keep board waste at a minimum. This type of carrier can be manufactured in quantity at reasonable cost and is particularly suited for use with certain articles to be packaged such, for example, as soft drinks, and is commonly referred to as a "strap" style carrier due to the shallowness of its transverse partitions.

In my Patent 2,688,421, granted September 7, 1954, and owned by the assignee of this invention, a carton is disclosed and claimed which is somewhat similar to the carrier disclosed and claimed in Patent 2,537,452. The carrier of Patent 2,688,421, however, is of the type wherein the medial and transverse partitions are substantially coextensive, with the carrier side walls and is therefore commonly known as a "full depth" type of carrier. As will be readily apparent, the so-called full depth carrier is of a more rugged construction than the so-called "strap" style carrier and naturally is more costly to manufacture.

I have found that the additional material required to make a full depth carton according to my above mentioned Patent 2,688,421 is needed primarily for its partitioning function and only secondarily to afford strength and rigidity to the structural support elements of the carrier. Stated otherwise, the carrier of my Patent 2,537,452 can be constructed generally along the lines of my Patent 2,776,072, issued January 1, 1957, and owned by the assignee of this invention, and when so constructed adequate support for heavy duty service is provided and the only further feature that is needed is to provide partitioning means which acts to cushion adjacent articles from each other.

A principal object of this invention is to provide a sturdy basic carrier structure which is adapted for ordinary carrier service and in addition, to provide cushioning partition means for rendering the basic carrier suitable for heavy duty service.

Another object of this invention is further to standardize carrier design so as to effect substantial cost reductions in the manufacture of carriers generally and at the same time to provide a carrier which is suitable for more than one type of service.

The invention in one form as applied to a carrier for a plurality of similar articles comprises a handle, a pair of partition strips integral with the handle and with the adjacent side wall and interrelated therewith along fold lines, an auxiliary panel forming a part of the handle panel, an auxiliary cushioning partition having a pair of panels arranged respectively to form downwardly extending continuations of said partition strips, and a third panel arranged to form a downwardly extending continuation of said auxiliary panel, and fastening means such as glue for interrelating said cushioning partition and the carrier structure to hold the cushioning partition in position.

While it is preferable to construct a carrier according to

2

this invention from paperboard, it will be understood that other materials may be used, such, for example, as plastic substances.

For a better understanding of the invention reference may be had to the following detailed description taken in conjunction with the accompanying drawings in which FIG. 1 is a perspective view of a carrier embodying the invention; FIG. 2 is a side view of the carrier depicted in FIG. 1; FIG. 3 is a cross-sectional view of the carrier depicted in FIGS. 1 and 2 and taken along the line indicated at 3—3 in FIG. 2; FIG. 4 is a plan view of a paperboard blank from which the carrier without its auxiliary partition is formed, i.e., from which a strap style carrier is formed according to this invention; FIGS. 5—9 inclusive depict progressive stages through which the blank of FIG. 5 is passed in forming a strap style carrier according to this invention; FIG. 10 is a plan view of an auxiliary element by which a strap style carrier is converted to a full depth type carrier in accordance with this invention; FIG. 11 is a view of the blank depicted in FIG. 10 from underneath and after the first folding operation and in which FIG. 12 is a fragmentary view taken on line 11—11 of FIG. 1.

With reference to the drawings and particularly with reference to FIGS. 1, 4 and 5, the numerals 1 and 2 designate side walls of the carrier while the numerals 3, 4, 5 and 6 denote end panels. End panels 3 and 4 are foldably connected with side wall 1 along fold lines 7 and 8 respectively while end panels 5 and 6 are foldably connected with side wall 2 along fold lines 9 and 10 respectively. Foldably joined to the bottom edge 11 of side wall 1 is bottom panel generally designated by the numeral 12 and which is provided with a medial fold line 13. Also foldably joined along the fold line 14 to the bottom wall 3 of the side panel 2 is a fastening flap generally designated at 15. Foldably joined along the fold line 16 to the end panel 3 is a riser panel in the form of medial partitioning support element 17. Similarly, riser panels in the form of medial partitioning support elements 18, 19 and 20 are foldably joined along lines 21, 22 and 23 to the end panels 5, 6 and 4 respectively.

The handle structure of the carton blank depicted in FIG. 5 is similar to that disclosed and claimed in my above mentioned Patent 2,537,452 and comprises two pairs of telescopically arranged panels designed in FIG. 5 by the numerals 24, 25, 26 and 27. Certain numerals are applied to FIG. 5 and certain other numerals are shown on FIG. 6 to prevent crowding. The panels 24—27 are generally similar to their overall arrangement and therefore only one of such panels will be described in detail, it being deemed desirable to point out, however, that the handle panel 24 is foldably joined to the handle panel 25 along the medial fold line 28 while the handle panel 25 is foldably joined to the handle panel 27 along the coincident fold line 29. Panel 24 is separated from panel 25 along a cut line 30 while panel 26 is separated from panel 27 along a cut line 31 which coincides with line 30. The outline of any one of the handle panels follows that for panel 24. The panel 24 may be defined by the points A, B, C, D, D', E, E', and F so that the area enclosed by the lines connecting these points A—F defines the one handle panel 24 which is disposed in a flat plane. Line A—B is a cut line separating handle panel 24 from end panel 5. Similarly, line C—D is a cut line separating partitioning strip 32 from an edge of handle panel 24 while line D—E' is a cut line a part of which coincides with line 30 and which separates panel 24 from panel 25. B—C is a fold line whereby the partitioning strip 32 is foldably connected with handle panel 24 while line G—H is a fold line along which the partitioning strip 32 is foldably joined with the side wall 2.

For the purpose of enabling the carrier to be readily

grasped by the hand of the person carrying it, aperture 33 is provided in handle panel 24.

In similar fashion hand hold aperture 34 and flap 35 adjoined to panel 25 by fold line 36 are provided. Hand hold apertures 37 and flap 38 adjoined to panel 27 by fold line 39 are provided in handle panel 27.

As is disclosed in my above mentioned Patent 2,537,452, additional partitioning strips 40, 41 and 42 are provided and are interrelated with the other elements as described in detail above in connection with partitioning strip 32, it being understood that the strips 40 and 42 in FIG. 5 are shown in dotted lines because they are underneath the folded inserts depicted in FIGS. 10 and 11.

The panel elements 24 and 26 are telescoped over panel elements 25 and 27 when the carton is formed as will be described in detail hereinafter.

According to a feature of this invention, an auxiliary panel is provided in one of the handle panels, such as 26. Such auxiliary panel is designated in the drawings by the numeral 43 and is separated from handle panel 26 along a cut line extending from the point designated I to point J and thence to points K and L. A perforated fold line designated by the numeral 44 is provided whereby the auxiliary panel 43 may be folded downwardly.

The first step in forming a carrier according to this invention is shown in FIG. 5. During this operation a cushion of FIG. 10 is folded and secured to strips 42 and 40. With reference to FIG. 10 it may be observed that the cushion comprises three panels 45, 46 and 47 formed by fold lines 48 and 49. Thus panel 47 is folded into flat contact with panel 46 along fold line 49, the panel 47 being underneath panel 46 is viewed in FIG. 10. As depicted in FIG. 11 the insert of FIG. 10 is turned over after the fold along line 49. The insert is then affixed to strip 42, the stippled area 50 in FIG. 11 being glued to the strip 42 so that the structure then appears as depicted in FIG. 5. A similar operation results in affixing an insert to strip 40 as shown in FIG. 5.

The next step in forming the carrier is shown in FIG. 6. This step comprises folding the auxiliary panel downwardly along the fold line 44, it being understood that the auxiliary panel 43 is maintained in the downwardly folded position due to glue indicated by stippling in FIG. 4. When so folded, the auxiliary panel 43 is disposed at the approximate level of the partition strips 32, 40, 41 and 42, as will be apparent from FIG. 6. Thereafter glue is applied to the blank depicted in FIG. 6 as indicated thereon by the stippled areas.

The blank is then folded as depicted in FIG. 7. Such a folding operation causes the end panels 3 and 5 to swing over the side panels 1 and 2 along the fold lines 7 and 9 respectively. Simultaneously, partitioning strip 32 swings over along the top center portion 2A of side panel 2 along the fold line G—H. The partitioning strip 41 folds similarly. During this operation, the stippled area of panel 45 as shown in FIG. 10 is affixed to the stippled area of strip 41 as shown in FIG. 5. Simultaneously strip 32 is secured to the other panel 45. Since A—B is a cut line and B—C is a fold line, the above described folding operation causes the handle panel 24 to overlap the strip 32 partially as depicted in FIG. 7. In similar fashion the corresponding end panel 3 and handle panel 26 are simultaneously folded over, it being under-

stood that the opening 33 coincides generally with the hand gripping opening 34 and the opening from which auxiliary panel 43 is struck overlies and generally coincides with the hand gripping aperture 37. The inner ends of panels 17 and 18 are secured to panels 26 and 24 respectively adjacent the fold lines 16 and 21. Medial support elements 19 and 20 are folded along their fold lines 22 and 23 respectively.

Thereafter an application of glue is made to the structure as shown in FIG. 7 and subsequently the arrangement is folded along the medial fold lines 28 and 29 to the position indicated in FIG. 8. The stippled areas of the two panels 46 are secured together in this operation.

It will be understood that the lap panel 15 is secured along an edge of the bottom panel 12 to complete the carrier structure depicted in FIG. 9, which figure shows the carrier in its collapsed condition.

As is well known, the carrier is maintained in its set up condition by locking notch 51 and its cooperating notch 52 as shown in FIG. 12.

While I have shown and described particular embodiments of the invention, I do not wish to be limited thereto and intend in the appended claim to cover all such changes and modifications as fall within the true spirit and scope of the invention.

What I claim as new and desire to secure by Letters Patent of the United States is:

An article carrier comprising a handle having two pairs of handle panels in telescoping face contacting relation, a pair of end panels foldably joined to each end of said handle, a pair of side walls foldably joined at each end thereof to a different one of said end panels along the edge thereof remote from said handle, a plurality of partition strips disposed in spaced relation between said end panels and each being foldably joined at one end to a different one of said handle panels and at the other end to one of said side walls to form a row of article receiving cells on each side of said handle, an auxiliary panel struck out of an inner one of said handle panels and folded downwardly to a position which is generally coplanar with the other handle panels and which extends between the adjacent ends of said partition strips, and a cushioning partition structure interposed between adjacent partition strips on each side of said handle, the structure on one side of said handle having a first cushioning panel in abutting face contacting relation with a complementary structure on the opposite side of said handle and with said auxiliary panel, glue means for securing said first cushioning panels to each other in face contacting abutting relation and to said auxiliary panel, a pair of cushioning panels foldably joined along vertical fold lines to each vertical edge of each of said first cushioning panels, and glue means for securing each one of said pairs of cushioning panels to the opposed faces of adjacent strips.
